UNDER KEYBOARD SWITCH

Merwin J. Larsen, Gainesville, Fla., assignor to Central Commercial Industries, Inc., Cook County, Ill., a corporation of Delaware

Application May 21, 1952, Serial No. 289,141

1 Claim. (Cl. 206—153)

This invention relates to electric switches and has particular reference to improvements upon the form of switch disclosed in United States Letters Patent to A. F. Evett, No. 2,573,895, issued November 6, 1951.

The herein disclosed invention is primarily formed, constructed and adapted for use with a keyboard musical instrument of the class and for the purpose set forth in United States Letters Patent No. 2,250,065 wherein electrical generators of audio tone signals are adapted to be selectively conducted to an electroacoustical translating system for activation of the latter and production of audible sounds when playing said keyboard.

The principal object of the invention is the provision of a simple, inexpensive and exceedingly compact organization or assembly of substantially similar electric switches that can be applied as a unitary structure to a piano inside the case thereof and underneath the keyboard to dispose the individual switches relative to respective playing-keys thereof for actuation of the switches from "off" conditions when the keys are raised to "on" conditions of said switches when the keys are lowered as when playing said keyboard.

Attempts heretofore made to adapt electric switches to the keys of a keyboard from underneath the latter and inside the case of a piano have proved unsuccessful and impractical for a number of reasons, notwithstanding the exercise of good judgment and great care when adjusting the individual switches to respective keys. Electric switches for use as herein proposed are characterized by coactive electrical contact elements. The playing-keys of the keyboard of a piano are tensioned by springs that tend to rock the keys in a direction which urges their front ends to playing positions. Devices are generally coactive with the keys for adjusting the tension of said springs in order that said front ends of the keys can be leveled and placed under such tension that allows the keys to be played when pressure of from two to four ounces is applied thereto. It has been discovered that variables in adjustment of the above named parts occur from time to time as a more or less natural consequence and that as a direct result thereof the front ends of the keys seek lower positions than originally intended and that and due thereto, the contact elements of the switches engage each other to the extent that the circuits in which they are connected are either partially or completely closed. This causes unwanted sounds to be produced which interfere materially with satisfactory playing the instrument.

An important object of my invention is the provision of an organization of similar electric switches, the key operated contactor of which automatically assumes a form and condition during initial application of the key to the mounting on which it has detachable connection and is free to rock vertically as to render the switch self compensatory once the contactor has assumed a change in its form as provided for during initial application of the key as aforesaid.

A further object resides in the general form and con-

struction of an organization of electric switches that enables said organization to be attached as a unitary structure to conventional parts of a piano, such as the mounting for the keyboard.

5 Other objects and advantages of the invention will be apparent upon reference to the following description and the accompanying drawings, wherein:

Figure 1 is a sectional perspective view of a portion of the case of a piano showing my improved organization of electric switches attached to the keyboard mounting of the piano;

Figure 2 is a fragmentary view in top plan of the keyboard mounting showing two of the switches in positions for actuation of respective keys, said keys being eliminated for the sake of clearness;

Figure 3 is a sectional perspective view of a portion of said switch organization showing the parts on an enlarged scale and illustrating the mode of attachment of the organization to a portion of the keyboard mounting;

Figure 4 is a schematic transverse section through the organization and a portion of the keyboard mounting illustrating a playing-key in a position of initial application to said mounting;

Figure 5 is a view similar to Figure 4 showing the key depressed to a position which is coactive with the switch actuator to change the angle of its effective key operated branch;

Figure 6 is a view similar to Figure 5, showing the contactor at rest against a fixed surface and the branch 20 bent to its final form;

Figure 7 is a view similar to Figure 6 with the key raised or in a playing position as distinguished from a completely depressed position of the key as shown in said Figure 6, and

Figure 8 is a transverse section of a conventional keyboard mounting and an associated key.

At Figure 3 of the drawings is a flat strip of Bakelite 10 on which is mounted an individual switch of my improved organization of similar switches. At Figure 1 the individual switches are disposed in a horizontal series or row with the switches longitudinally spaced apart from each other, such that there will be a switch for and coactive with each playing-key of a conventional key-

board. The switch shown at Figure 3 and the switches shown at Figures 1, 2 and 4 to 7, are identical in every respect and a description of one thereof will suffice for all and enable their structural features to be identified by like reference numerals. 12 and 13 are vertically spaced apart bus-bars supported by blocks 14 of insulating material secured to the upper face of said strip 10. A key operated actuator 15 comprising a flat strip of metal is tiltably mounted on said strip 10, and, as shown, said actuator includes a substantially rectilinear flat portion 16 of suitable length having at one of its ends a depending lug 17 which is freely received in a slot 24 in said strip 10 so that said contactor can tilt vertically. The other end of said portion 16 is formed with lower and upper angularly related branches 19 and 20 which are joined to each other by a curved portion 21. Said portion 16 passes through the space between said bus-bars 12 and 13 and same is provided with a longitudinally extending slot 22 for a purpose to be described later.

Secured to strip 10 is a terminal clip 25. A coil retractile spring 26 has one of its ends fixed to said clip and its other end attached to a lug 23 which is upset from said portion 16. By connecting the spring to said clip 25 and to said lug 23 in the manner shown, the spring is free to be flexed laterally and its flexure compensated for by said slot 22 as will be appreciated upon reference to Figures 4 to 7 of the drawings. The spring tends always

to tilt the actuator in an upward direction in order that its normal coactive relationship to an associated playing-key will be maintained. It is noted that said spring passes through the space between said bus-bars 12 and 13 and that it functions both as an electrical conductor and as a resilient means tending to tilt the actuator as aforementioned. The clip 25 is adapted to be connected in circuit with a signal supply so that when the key is depressed, signal current will be conducted through an electrical network in response to actuation of a playing-key. Bus-bar 12 is connected to ground G. The spacing between bus-bars 12 and 13 is such that by vertical motion of said actuator, first downwardly and then upwardly, the spring alternately makes and breaks electrical contact therewith, such that when an associated playing-key is in a playing or rained position the signal supply source will be connected to ground via said bus-bar 12, whereas, when the key is depressed or lowered as when played, the signal supply source will be coactive with bus-bar 13, which latter can be connected to any well known electroacoustical translating system for conversion of signal current into audible sound.

Said actuator 15 is formed of metal having a low degree of resiliency. Dead soft steel of about 10,000 inch gauge has been found entirely suitable for the purpose of the invention. Its width may be approximately $\frac{1}{16}$ of an inch and the length of the portion 16 from lug 17 to the bend 21 is about one and a half inches. The length of the branch 20 is approximately nine-sixteenths of an inch. It is not intended that the actuator shall be confined to the specific proportions above stated. The diameter of the coil spring is about $\frac{3}{32}$ of an inch and the width of the slot 22 is about $\frac{5}{32}$ of an inch. Reference will be made herein to the terms "relatively ductile," "slightly resilient" and "low degree of resiliency" when describing the properties of the metal from which the key operated actuator 15 is formed. These terms shall be construed to mean that the portion 16 is of sufficient strength to resist flexure under tension of said spring and that when the branch 20 of said actuator is bent from an initial angle to a permanent angle, it will yield only very slightly under any key pressure imposed thereon. At no time will it yield to an extent that the spring 26 will move off of the grounding bus-bar and onto the signal output bus-bar merely by the weight of the key.

Now, and with particular reference to Figure 4 of the drawings, it is noted that branch 20 of the key operated actuator 16 occupies an initial or non-permanent angle, such that when K is being applied to its guide and fulcrum pins 27 and 28, said branch 20 will have its extreme free end disposed at an elevation which is higher than a substantially horizontal playing position of the key and thus in a position where it will be pressed against by the key when depressing same a first time. Upon further downward motion of the key, branch 19 of the actuator 15 is advanced against an insulating surface 29 upon a rigid metal plate 30. This squashes branch 20 with a resultant change in its angular relation to said branch 19. By this means, said branch 20 is changed from a non-permanent angle relative to branch 19 as shown at Figure 4 to a permanent or set angle relative thereto as shown at Figures 6 and 7, in the latter of which the playing-key is in a normal substantially horizontal position.

An essential feature of the invention is the provision of an organization of switches for use under the playing-keys of a conventional piano keyboard, or the keyboard of an organ or other keyboard musical instrument. A keyboard of this type is usually mounted upon a base structure 31 which includes a longitudinal front strip 32 on which guide pins 27 are mounted. At the back, said mounting is provided with a similar longitudinal strip or fulcrum bar 34 having the customary fulcrum pins 28. The strip 32 and said fulcrum bar 34 are connected together by transverse bars 28a. The space between strip 32 and bar 34 accommodated the aforementioned strip 10,

and, as shown, said strip rests flatwise against the upper surface of said cross bars 28a. The metal plate 30 is secured at 35 to the rear portion of said strip 32 in a manner to cause the underside of said strip to rest firmly on said bars 28a.

Upon referring to Figure 1, the signal input lead wires to the respective springs 26 of the individual switches are shown at 37 and same are formed into a cable 38 which extends longitudinally of the switch organization.

From the foregoing description, it is only necessary that the keys of a conventional keyboard be removed so as to expose the underlying key mounting from which the keys are readily separable. The key switch organization is then applied to the mounting and attached to the front strip 32, all as clearly shown at Figures 4 to 7 of the drawings. The switches are spaced apart from each other so that for each playing key there is a switch individual thereto and adapted to be operated by the key.

The process of reinserting the keys is then in order and this is accomplished by individually inserting the keys into the instrument so that each key is operatively connected to a respective fulcrum pin 28. The forward end of the key is then vertically aligned with a respective guide pin 27. In this operation, the key will approximately occupy the position shown at Figure 4. Under the urge of spring 26, contactor 15 will be tilted in an upward direction and against the underside of the key. It will be borne in mind that at this instant the branch 20 of the actuator is at a non-permanent angle relative to branch 19. Pressure is progressively applied against the key so as to move the actuator downwardly against the normal urge of spring 26 and until branch 19 comes substantially flat-wise against the insulated face of the rigid metallic strip 30. It is noted that at Figure 6 the key has been fully depressed and that branch 20 has been squashed or bent from a non-permanent angle as shown at Figure 4 to a permanent angle, such that when the angle has once been changed by the initial placement of the keys in an instrument it is never changed and is, therefore, capable of uniform coaction with the key at all times.

Heretofore it has been impossible to properly correlate the actuator of an electric switch with a vertically tiltable key so that by means of identical switches, there will be no variables in the time in which a circuit is made and broken. In the instant case, the springs 26 always urge the free ends of the branches 20 against the undersides of their respective playing keys. The gist of the invention lies in the self-compensatory action of the actuator. By this is meant that when applying the keys to an instrument in the manner aforementioned the actuators will be operated upon by the keys and their portions 20 bent from the non-permanent angles shown at Figure 4 to the permanent angle shown at Figure 7.

When pressure is released from a key the latter is returned to its normal playing position under the tension of spring 26. The branch 20 of the actuator maintains its fixed angle except possibly for some slight degree of resiliency in the metal which causes it to bear very lightly against the underside of the key.

While I have referred to use herein of dead soft steel of which the actuator 15 is constructed, this is by illustration only and it is to be understood that any well known equivalent material can be substituted therefor. The retractile spring 26 can also be made of any suitable well known material which is a good conductor of electricity to beryllium wire or copper wire has been found entirely satisfactory.

What I claim as my invention is:

A single pole, double throw electric switch comprising a mounting member of electrical insulating material having a grounding element and a signal output element, said signal output element and said grounding element supported in vertical spaced-apart relation to each other, a contactor of springy material attached to said mounting member and related to and coactive with said grounding

element and said signal output element for engagement first with one and then the other thereof and formed and adapted normally to yieldingly engage said grounding element, and pressure-responsive means coactive with said contactor to move same off of said grounding element and onto said signal output element when pressure in one direction is applied to said means, said pressure-responsive means tiltably connected to said mounting member for vertical motion and said contactor comprising a

coil spring, one end of which is secured to said mounting member and the other end thereof to the pressure-responsive means to normally urge said means against said grounding element, as and for the purpose set forth.
